UNITED STATES PATENT OFFICE.

GEORGE D. DODGE, OF CHICAGO, ILLINOIS.

SHADE OR CURTAIN ATTACHMENT.

1,196,846.

Specification of Letters Patent. Patented Sept. 5, 1916.

Application filed October 25, 1915. Serial No. 57,681.

To all whom it may concern:

Be it known that I, GEORGE D. DODGE, a citizen of the United States, residing at Chicago, county of Cook, State of Illinois, have 5 invented a certain new and useful Improvement in Shade or Curtain Attachments, and declare the following to be a full, clear, and exact description of the same, such as will enable others skilled in the art to which it 10 pertains to make and use the same, reference being had to the accompanying drawings, which form a part of this specification.

My invention has for its object to provide a simple and novel means for effectively 15 guiding the free end of a shade or curtain so as to prevent it from swinging outwardly from the opening across which it extends and flapping about in the wind.

The various features of novelty whereby 20 my invention is characterized will herein-after be pointed out with particularity in the claims; but, for a full understanding of my invention and of its object and advantages, reference may be had to the following de- 25 tailed description taken in connection with the accompanying drawing, wherein:

Figure 1 is an elevation of a portion of a window and its frame across which extends a shade equipped in accordance with the 30 present invention; Fig. 2 is a section on an enlarged scale taken approximately on line 2—2 of Fig. 1; and Fig. 3 is a section on the same scale as Fig. 2 approximately on line 3—3 of Fig. 1.

Referring to the drawing, 1, 1 represent 35 the side members of a window frame and 2 is a shade lying between said members. On the members 1, 1 are arranged vertical tracks, 3, which are preferably made of long 40 flat metal strips having their side edges bent inwardly so as to give a cross sectional shape like that of an elongated C. These tracks, when fastened directly to the window frame are practically unnoticeable because they 45 hug the frame and make a projection thereon which need not be over one-eighth of an inch in thickness. On the shade are slides 50 or shoes, 4, which interlock with the tracks, being free to ride up and down the same but 55 being held against movement relatively thereto in any transverse direction. In the broadest aspect of my invention, these slides or shoes, which are also comparatively thin and flat, may be secured to the opposite edges of the shade in any suitable way. In 60 the more elaborate form of my invention

illustrated, however, means are provided for allowing play between the slides or shoes and the shade, transversely of the shade and in the plane of the latter, so that there will 60 be no danger that the shade will bind as it travels up and down if it should happen, as is usually the case, that the window frame is warped more or less. In the arrangement shown, I have provided U-shaped clips, 5, 65 which are slipped over the shade stick of an ordinary shade and secured thereto in any suitable manner. On the under side of each clip is a finger piece comprising a flat head, 6, and a square or flattened neck, 7, the 70 necks of the finger pieces being provided with stems, 8, which pass through the yoke portions of the clips and are riveted over so as to hold the finger pieces in place while permitting them to be rotated about their 75 own axes. Extending laterally from each of the slides or shoes is a finger, 9, adapted to underlie the corresponding clip and provided with a slot, 10, extending lengthwise thereof for the passage of the head of the 80 finger piece. The slots 10 are long enough to permit the passage of the parts 6 but have a width only slightly greater than the thickness of said parts. The result is that when the finger pieces are slipped through the 85 slots and are then turned through an angle of ninety degrees, the slides or shoes are locked to the clips, relative movements being permitted however in the direction of the length of the slots; such relative move- 90 ments being sufficient to prevent the shade from binding as it is raised and lowered. In order to prevent the finger pieces from being turned accidentally out of their locking positions, the necks, 7, are made square or flat 95 as heretofore explained and of such a size that they will have a sliding fit and be prevented from turning in the slots. Each of the slots is provided at its outer end with an enlargement, 11, giving it the appearance of a 100 keyhole slot, and this enlargement is of a size sufficient to receive the neck of the corresponding finger piece and permit the latter to turn so as to permit the head to be shifted from a position across the slot to one parallel with the length thereof. It will thus be 105 seen that the shade can be readily connected to or disconnected from the slides or shoes but, after being connected thereto, will be securely held against accidental uncoupling. 110

While I have illustrated and described with particularity only a single preferred

form of my invention, I do not desire to be limited to the exact structural details thus illustrated and described; but intend to cover all forms and arrangements which 5 come within the terms employed in the definitions of my invention constituting the appended claims.

I claim:

1. In combination, a frame, a shade extending across the frame, tracks on the frame at opposite sides of the shade, slides or shoes interlocked with the tracks and movable along the same, members containing elongated slots extending from said slides 15 or shoes into proximity to the shade, and headed members projecting from the shade loosely through said slots so as to be freely movable along the slots.

2. A shade fixture comprising, a clip 20 adapted to be secured to a shade, a track, a shoe interlocked with the track, an arm on

the shoe having a key-hole slot, and a member on said clip having a flat head adapted to pass freely through said slot in one relative position and to lock the clip and shoe 25 together in other relative positions.

3. A shade fixture comprising, a clip adapted to be secured to a shade, a track, a shoe interlocked with the track, an arm on 30 the shoe having a key-hole slot, a member on said clip having a flat head adapted to pass freely through said slot in one relative position and to lock the clip and shoe together in other relative positions, and said member having a neck beneath the head so shaped as 35 to prevent said member from being turned relative to the shoe except when said neck is in the enlarged end of the slot.

In testimony whereof, I sign this specification.

GEORGE D. DODGE.
